ORTHOPTIC INSTRUMENT

Alfred W. Sorenson, Racine, Wis., assignor to Visual Therapy Products Corporation, Racine, Wis., a corporation of Wisconsin

Application December 29, 1958, Serial No. 53,954

Term of patent 7 years

(Cl. D57—1)

FIG. 3

FIG. 2

FIG. 1

Fig. 1 is a side elevational view of an orthoptic instrument showing my new design.

Fig. 2 is a front elevational view of the instrument shown in Fig. 1.

Fig. 3 is a top plan view of the instrument shown in Fig. 1.

I claim:

The ornamental design for an orthoptic instrument, substantially as shown.
